US0D1076902S

(12) **United States Design Patent** (10) **Patent No.:** **US D1,076,902 S**
(45) **Date of Patent:** **** May 27, 2025**

(54) **COMBINED PHONE STAND AND SPEAKER**

(71) Applicant: **Wu Liu**, Hunan (CN)

(72) Inventor: **Wu Liu**, Hunan (CN)

(**) Term: **15 Years**

(21) Appl. No.: **29/964,447**

(22) Filed: **Sep. 23, 2024**

(51) **LOC (15) Cl.** **14-03**

(52) **U.S. Cl.**

USPC **D14/252**

(58) **Field of Classification Search**

USPC D14/217, 251-253, 242-243, 447, 172;
D13/108

(57) **CLAIM**

The ornamental design for a combined phone stand and speaker, as shown and described.

DESCRIPTION

FIG. 1 is a perspective view of a combined phone stand and speaker showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the combined phone stand and speaker of FIG. 1 in an expanded position; and,

FIG. 10 is another perspective view thereof.

The broken lines depict portions of the combined phone stand and speaker that form no part of the claimed design.

1 Claim, 10 Drawing Sheets
